UNITED STATES PATENT OFFICE

158,785

MEMORANDUM PAD HOLDER

Hjalmer K. Peterson, St. Paul, Minn.

Application April 8, 1949, Serial No. 1,874

Term of patent 7 years

(Cl. D74—1)

To all whom it may concern:

Be it known that I, Hjalmer K. Peterson, a citizen of the United States, residing at St. Paul, county of Ramsey, and State of Minnesota, have invented a new, original, and ornamental Design for a Memorandum Pad Holder, of which the following is a specification, reference being had to the accompanying drawing, forming part thereof.

I claim:

The ornamental design for a memorandum pad holder, as shown.

HJALMER K. PETERSON.
